US00D859302S

(12) **United States Design Patent** (10) Patent No.: **US D859,302 S**
 Severyn et al. (45) Date of Patent: ** Sep. 10, 2019

(54) **TIRE**

(71) Applicant: **Bridgestone Americas Tire Operations, LLC**, Nashville, TN (US)
 (72) Inventors: **David M. Severyn**, Akron, OH (US);
Michael J. Kubiak, New Franklin, OH (US); **Seth M. Ricks**, Canton, OH (US); **Dennis D. Belden, Jr.**, Canton, OH (US)

(73) Assignee: **Bridgestone Americas Tire Operations, LLC**, Nashville, TN (US)

(**) Term: **15 Years**

(21) Appl. No.: **29/648,783**

(22) Filed: **May 24, 2018**

(51) LOC (12) Cl. **12-15**

(52) U.S. Cl.

USPC **D12/604**

(57) **CLAIM**

The ornamental design for a tire, as shown and described.

DESCRIPTION

FIG. 1 is a side perspective view of a tire showing our new design;

FIG. 2 is a front elevational view thereof;

FIG. 3 is a side elevational view of the left side thereof; FIG. 4 is a side elevational view of the right side thereof; and,

FIG. 5 is an enlarged fragmentary view thereof.

In the drawings, the broken lines depict environmental subject matter only and form no part of the claimed design.

1 Claim, 5 Drawing Sheets
